T. W. KIRKMAN.
ELECTRICAL FUSE.
APPLICATION FILED JUNE 6, 1916.

Patented Aug. 14, 1917.

By his Attorney

Robert M. Pearson

UNITED STATES PATENT OFFICE.

THOMAS W. KIRKMAN, OF NEW YORK, N. Y.

ELECTRICAL FUSE.

1,236,448.

Specification of Letters Patent. Patented Aug. 14, 1917.

Application filed June 6, 1916. Serial No. 101,903.

To all whom it may concern:

Be it known that I, THOMAS W. KIRKMAN, a citizen of the United States, residing at New York city, in the county of New York and State of New York, have invented certain new and useful Improvements in Electrical Fuses, of which the following is a specification.

This invention relates to the construction of electrical fuses and especially those of the larger sizes employing flat copper terminals or electrodes. It has heretofore been a difficult matter to provide an inexpensive and efficient form of connection between the casing and the terminals, principally on account of the difficulty of drilling and screw-threading copper, and it is the principal object of my invention to provide a fuse which will avoid the necessity of performing either or both of these operations.

Of the accompanying drawings,

Figure 1 represents a longitudinal section of an electrical fuse device embodying my improvements and constructed as a refillable fuse.

Fig. 2 represents a section on the line 2—2 of Fig. 1.

Fig. 3 represents a section on the line 3—3 of Fig. 1.

Fig. 4 represents an edge view of a modified form of fuse terminal.

Fig. 5 represents a section on the line 5—5 of Fig. 4.

Fig. 6 represents an edge view of a second modification.

Fig. 7 represents an edge view, partly in section, of a third modification, which is of the non-refillable type.

Fig. 8 represents an inner-end view of the form shown in Fig. 7.

Referring at first to Figs. 1, 2, and 3, 10 indicates the cylindrical tubular casing of vulcanized fiber having sheet-metal caps 11, 11 on its ends to retain the powdered filling 11 material (not shown) and to form a part of the connection between the casing and the terminals, these caps being perforated at 12 to permit the escape of gases, and diametrically slotted at 13 to admit the passage of 20 the copper terminals or electrodes 14.

Each electrode in this form of my invention is made up of a pair of plates riveted together at 15 near their outer ends and separated at their inner ends to receive between them the end of the fuse strip 16 which may be of any suitable character, the

fuse strip being secured to the electrode plates by a bolt 17, which permits the fuse strip to be renewed by the user.

18 are attaching screws having screw-threaded engagement with holes in the casing 10, and passing loosely through holes in the metal caps 11, said screws at their inner ends engaging the copper terminals 14 and serving detachably to connect said terminals with the caps and casing. The stems of the screws occupy recesses or niches 19 at opposite points on the margins of the electrodes 14, each recess being formed by punching out a piece from one of the electrode plates and bending the wall of the adjacent plate, as indicated at 20, by suitable dieing operations performed in a press.

The engagement of the terminal 14 with the sides of the slot 13 in cap 11 prevents relative rotation of said cap and terminal, and the screws 18 prevent relative rotation as well as longitudinal movement of the cap 11 and casing 10. The terminal 14 is accordingly prevented from rotating with respect to the casing, and it is also prevented from moving longitudinally with respect thereto by reason of the occupation of the recesses 19 by the screws 18. The terminal is furthermore prevented by the screws from swinging or tilting on the edges of slot 13, it being noted that the offsets 20 on the respective margins are located on opposite sides of the terminal so as to prevent this action in both directions. I thus provide an effective means of detachably and securely connecting all of the parts and avoid the expensive operations of drilling and tapping the copper terminals, or attaching the latter to the casing by means of various devices of a less simple nature than the present expedient. Ordinarily no tapping of the screw-holes in the casing 10 is required, as the screws will form their own threads in the relatively-soft material of the casing.

The modification shown in Figs. 4 and 5 consists in bending double a single strip of copper forming the electrode 14^a, and offsetting both plates of this electrode to make circular recesses or holes 19^a for the reception of the attaching screws.

Fig. 6 differs from Figs. 4 and 5 in that one of the plates is punched through on each margin of the electrode, forming a recess 19 of the same character as in Figs. 1, 2, and 3.

Figs. 7 and 8 show a modification in

which the electrode consists of a single strip of copper provided with offsets 20 forming recess 19^b for the screws, and also provided with an offset at 21 in which the end of a bundle of fuse wires 22 is soldered, this form being less adapted than the others to be refilled by the user.

Various other modifications may be made within the scope of my invention.

10 I claim,

1. An electrical fuse device comprising a tubular casing, a cap on the end thereof, an electrode in the end of said casing, having an offset forming a recess, and an attaching member connecting said parts together and occupying said recess.

2. An electrical fuse device comprising a tubular casing, a cap on the end thereof formed with a diametrical slot and oppositely-located holes, a pair of screws threaded in holes in said casing and passing through the holes in said cap, and a copper electrode traversing the slot in said cap and oppositely offset on its margins to form

recesses occupied by the inner ends of the 25 screws.

3. An electrical fuse device comprising a tubular casing, a diametrically-slotted cap on the end thereof, a flat electrode occupying the slot in said cap, and means connecting said members and locking the electrode against movement with respect to the casing in all directions, the casing having inwardly-projecting means and the electrodes being laterally offset to provide said connecting means.

4. An electrical fuse device comprising a tubular casing, a cap thereon, a pair of copper plates in the end of said casing forming an electrode and held from rotation with respect to said cap, said electrode having its margin offset to form a recess, a screw connecting the cap and casing and occupying said recess, and a fuse strip detachably clamped between said electrode plates.

In testimony whereof I have hereunto set my hand this third day of June, 1916.

THOMAS W. KIRKMAN.
